DESIGN FOR A LADY'S COAT

Louis Schneider, New York, N. Y.

Application July 31, 1936, Serial No. 64,147

Term of patent 3½ years

To all whom it may concern:

Be it known that I, Louis Schneider, a citizen of the United States of America, residing in Manhattan, county of New York, and State of New York, have invented a new, original, and ornamental Design for a Lady's Coat, of which the following is a specification, reference being had to the accompanying drawing, forming part thereof, wherein,

Figure 1 is a front view of a lady's coat showing my new design.

Figure 2 is a rear view of the lady's coat shown in Figure 1.

The dotted lines occurring along the front and back shoulder seams represent stitching.

The design is characterized by strands of wool tying into an ascot at the front neckline, and pulled through slits at the rear of the collar portion in combination with the coat, as shown.

I claim:

The ornamental design for a lady's coat, substantially as shown, and described.

LOUIS SCHNEIDER,
